The ornamental design for an oven protector as shown and described.

DESCRIPTION

FIG. 1 is a perspective view of an oven protector showing my new design;

FIG. 2 is a right-side view thereof;

FIG. 3 is a left-side view thereof;

FIG. 4 is a top view thereof;

FIG. 5 is a bottom view thereof;

FIG. 6 is a front view thereof;

FIG. 7 is a back view thereof;

FIG. 8 is an enlarged detail of portion 8 indicated in FIG. 1; FIG. 9 is an enlarged detail of portion 9 indicated in FIG. 4; FIG. 10 is an enlarged detail of portion 10 indicated in FIG. 5;

FIG. 11 is another perspective view thereof, shown in a configuration of use; and,

FIG. 12 is an enlarged detail of portion 12 indicated in FIG. 11.

The broken lines in the drawings depict portions of the oven protector that form no part of the claimed design. All areas of the top and bottom surface of the oven protector are similar to the zoomed in portions shown in FIGS. 9-10.
